Primary Examiner — Susan E Krakower(74) *Attorney, Agent, or Firm* — Mark D. Trenner; Trenner Law Firm, LLC**CLAIM**

The ornamental design for a chinstrap, substantially as shown in the attached drawings.

DESCRIPTION

FIG. 1 is a perspective view of a chinstrap showing my new design in condition of use;

FIG. 2 is a front elevational view thereof;

FIG. 3 is a rear elevational view thereof;

FIG. 4 is a left side elevational view thereof, the right side elevational view is a mirror image and therefore not shown;

FIG. 5 is a top plan view thereof; and,

FIG. 6 is a bottom plan view thereof.

The broken lines showing a human head and neck, illustrate environmental structure which forms no part of the claimed design.
